United States Patent Office

Des. 211,346
Patented June 11, 1968

211,346

ORRERY

Philip S. Egan, Evanston, Ill., assignor to A. J. Nystrom and Co., Chicago, Ill., a corporation of Delaware

Filed July 19, 1967, Ser. No. 7,888

Term of patent 14 years

(Cl. D25—1)

I claim:

The ornamental design for an orrery, as shown.
